UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN EXTENSION FOR OVAL BRACKET-BACKS.

48,825.

Specification for Design.

Patented Apr. 4, 1916.

Application filed February 7, 1916. Serial No. 76,858. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Extension for Oval Bracket-Backs, of which the following is a specification, reference being had to the accompanying drawing, forming part thereof.

Figure 1 is a side view of an extension for oval bracket backs, showing my new design. Fig. 2 is a front view of the same.

I claim:

The ornamental design for an extension for oval bracket backs, as shown.

CHARLES E. JONES.
